(57) **CLAIM**

The ornamental design for a reflective chain insert, as shown and described.

DESCRIPTION

FIG. 1 is a top perspective view of a reflective chain insert; FIG. 2 is a bottom perspective view of a reflective chain insert;

FIG. 3 is a front view of a reflective chain insert;

FIG. 4 is a rear view of a reflective chain insert;

FIG. 5 is a top view of a reflective chain insert;

FIG. 6 is a bottom view of a reflective chain insert;

FIG. 7 is a right side view of a reflective chain insert;

FIG. 8 is a left side view of a reflective chain insert; and,

FIG. 9 is a view of a reflective chain insert shown in a configuration of use.

The broken lines in the drawings illustrate portions of the reflective chain insert or the environment incorporating the reflective chain insert that form no part of the claimed design.

1 Claim, 5 Drawing Sheets
